(57) **CLAIM**

The ornamental design for a radiator for an electronic device, as shown and described herein.

DESCRIPTION

FIG. 1 is a top, front, and right side perspective view of a radiator for an electronic device, according to the present invention;

FIG. 2 is a front view of the a radiator for an electronic device of FIG. 1;

FIG. 3 is a rear view of the a radiator for an electronic device of FIG. 1;

FIG. 4 is a left side view of the a radiator for an electronic device of FIG. 1;

FIG. 5 is a right side view of the a radiator for an electronic device of FIG. 1; and,

FIG. 6 is a top view of the a radiator for an electronic device of FIG. 1.

The bottom of the a radiator for an electronic device is flat and unornamented.

The portions of the disclosure that are shown in broken lines form no part of the claimed design.
